UNITED STATES PATENT OFFICE.

WILLIAM H. NICHOLLS, OF BROOKLYN, NEW YORK.

MOLDING MACHINE.

1,403,809.

Specification of Letters Patent. Patented Jan. 17, 1922.

Application filed November 22, 1920. Serial No. 425,790.

To all whom it may concern:

Be it known that I, WILLIAM H. NICHOLLS, a citizen of the United States, and resident of the borough of Brooklyn, in the county 5 of Kings, city and State of New York, have invented certain new and useful Improvements in Molding Machines, of which the following is a specification.

This invention relates to improvements 10 in apparatus for forming molds and has for its general object the provision of means for jolting or jarring the sand in a flask or flask member, squeezing or compressing the sand about the pattern, and drawing the 15 pattern from the mold or mold section, during a single operation of the apparatus.

Another object of the invention is to provide a molding machine having two relatively movable pressure heads for pressing 20 the sand about the pattern in the flask or flask members and a pneumatic means carried by one of the pressure heads for automatically drawing the pattern when the pressure heads are separated.

25 Another important object of the invention is to provide a molding machine having a reciprocable flask supporting member, a normally stationary pressure head adapted to be swung laterally into and out of the 30 path of the flask supporting member, a pneumatic pattern drawing means being carried by said pressure head and adapted to be engaged by the pattern or pattern plate when the flask support is moved toward the 35 pressure head.

Another object of the invention is to provide a molding machine of the squeezer type having a pneumatic pressure head adapted to be engaged by the pattern plate and to 40 hold and draw said plate from the mold upon separation of the pressure head and mold.

In the accompanying drawings:

Fig. 1 is a side elevation of the apparatus 45 partly in vertical section;

Fig. 2 a horizontal sectional view of the main air control valve taken on line II-II of Fig. 3;

Fig. 3 a vertical sectional view of the main 50 air control valve;

Fig. 4 a detail sectional view showing the manner of packing the main piston;

Fig. 5 a plan view of the apparatus, the 55 normally stationary pressure head being shown swung laterally;

Fig. 6 a vertical sectional view of the normally stationary pressure head and its air control valve;

Fig. 7 a view similar to Fig. 6 showing the flask and pattern plate separated; and 60

Fig. 8 a detailed sectional view of the air control valve for the normally stationary pressure head.

In the embodiment of the invention illustrated in the drawings, the base 1 of the machine is formed at its upper end with a cylinder 2 having an open upper end. A large hollow piston 3 having an open upper end is adapted to reciprocate vertically in the cylinder 2 and is formed with a small central 65 cylinder 4. The cylinder 4 has an open upper end and a port 5 communicating with the interior of the hollow piston 3. A small jolt piston 6 is adapted to reciprocate vertically in the cylinder 4 relatively to the 70 main piston and said jolt piston is rigidly held to the under side of a pressure head or flask support 7 which normally rests on the 75 upper end of the piston 3.

Brackets 8 and 8^a extend horizontally from 80 opposite sides of the cylinder 2 and a valve for controlling the supply of fluid pressure to the cylinders 2 and 4 is mounted on the bracket 8. This controlling valve comprises a horizontally divided two-part casing 85 9 in which is mounted a rotatable valve disk 10 having two recesses 11 and 12 in the under side thereof and two pairs of oppositely disposed lugs 13 on the upper side thereof. The valve disk is adapted to be 90 rotated by means of a handle 14 fixed on the upper end of a valve stem 15, the lower end of which is formed with oppositely extending arms 16 which engage between the pairs of lugs 13 on the valve disk. A spring 17 95 coiled about the valve stem serves to press the valve disk upon its seat. The valve casing is provided with four openings 18, 19, 20, and 21 extending through the bottom thereof. The opening 18 communicates with 100 a flexible pipe 22^a connected with a pipe 22 which extends through the jolt piston 6 and communicates with the interior of the small cylinder 4. The opening 19 communicates with an air supply pipe 23 connected with 105 a suitable source of compressed air. The opening 20 communicates with a pipe 24 leading to a recess 25 in the bottom of the cylinder 2. The opening 21 leads to the atmosphere and preferably has a pet cock 110.

26 threaded therein to regulate the amount or rate of the exhaust. In order to prevent leakage past the large or squeezing piston 3 said piston is formed with a circumferential 5 channel 27 in which is seated a split packing ring 28 preferably formed with a V-shaped channel 29 in its inner side. Air under pressure is admitted from the cylinder 2 into channel 27 at the inner side of 10 the packing ring 28 through a plurality of 15 passages 30.

An upright post 31 is rigidly held in a 20 boss 32 formed on the bracket 8^a. A collar 33 is rigidly held to the post 31 adjacent 25 the upper end of the post, and a laterally swinging arm 34 is pivotally held at one end 30 to the post between said collar 33 and a collar 35 which is locked on the post by a nut 36. A vertically extending rod 37 is rigidly held at its upper end by nuts 38 to the free end of arm 34. The lower portion of rod 37 is adapted to engage in a slot or recess 39 formed in one side of a boss 40 on the bracket 8, and a nut 41 is threaded on the lower end of said rod and is adapted to engage under the boss 40 to resist upward pressure against the arm 34. The rod 37 and boss 40 serve also to limit the movement of arm 34 in one direction to arrest 35 the upper pressure head at a point in register with the lower pressure head 7.

The upper pressure head or member comprises a rectangular block 42 rigidly held to the lower end of a screw 43 threaded through the arm 34 midway the ends of 40 said arm. Formed in the head 42 is a cylindrical chamber 44 which is open at its lower end on the face of the pressure head. Fitting and sliding snugly in the chamber 44 is a suction piston 45, said piston being secured to the lower end of a vertically extending piston rod 46, said rod passing upwardly through a central bore in the screw 43. Secured to the upper end of the screw 45 above the arm 34 is a cylindrical casing 47 in which reciprocates a piston 48, said piston being rigidly connected to the upper end of the piston rod 46. The lower face of the pressure head 42 is grooved to receive a sealing ring or gasket 49. Air supply pipes 50 and 51 lead to the inner ends of the cylinders 44 and 47 and these pipes are connected to an air control valve 52 mounted on the arm 34. The air control 55 valve 52 comprises a two-part casing forming a valve chamber in which is arranged a rotatable disk valve 53 provided with recesses 54 and 55 in its outer face. The valve casing is formed with two exhaust ports 60 56 and 57 which may be placed in communication with the pipes 50 and 51 by rotating the valve disk 53 to the proper position. An air supply pipe 23^a enters the valve casing and is adapted to be placed in communication 65 with either of the pipes 50 or 51 by

means of the recesses 54 and 55. As shown in Fig. 6, the supply pipe 23^a is in communication with pipe 50 through recess 55, while pipe 51 is in communication with exhaust passage 57 through recess 54. In Fig. 7 the positions of the ports are reversed and the supply pipe 23^a is in communication with the pipe 51, pipe 50 being open to exhaust through the recess 55 and exhaust port 56. The ports 56 and 57 may be provided with pet cocks 58 to regulate the amount or rate of exhaust. The valve disk 53 is held to its seat by spring 59 and may be rotated through handle 60 and stem 61 connected to said valve in any suitable manner. A portion of the supply pipe 23^a and the pipes 50 and 51 are preferably flexible hose in order to permit the arm 34 to be swung on the post 31.

The squeezing piston 3 is held against rotation in its cylinder 2 by means of a post 62 rigidly held to the cylinder head and extending upwardly through an aperture in the head of the hollow squeezing piston. The post 62 is formed with a head 63 at its upper end which serves to prevent accidental forcing of the piston 3 out of the cylinder 2. The pressure head 7 and jolt piston 6 are held against rotation by a pin 64 depending from the head 7 and passing through an aperture in a spider 65.

The mold frame 66 may be of any suitable construction. As shown, said frame comprises one section of the well-known interchangeable cope-and-drag, divided metallic flask having the usual lateral projections or handles 67 each of which is provided with a rigid upwardly extending pin 68. The usual bottom board 69 fits within the lower end of the mold frame or flask 100 section 66. The pattern plate 70 may be of any suitable material and is formed with the usual handle portions or lugs 71 each of which is provided with an aperture adapted to receive the pin 68. The patterns 72 are 110 secured in the usual manner to the under side of the pattern plate.

To form a mold the flask and pattern are placed on the head 7 with the pattern plate resting on the head, and the flask is then 115 filled with sand. The handle 14 is then turned to permit air to flow from the source of supply through the pipe 23, port 19, valve cavity 11, port 18 and pipe sections 22^a and 22 into the small cylinder 4 beneath 120 jolt piston 6. The piston 6 and head 7 will thus be elevated slightly until exhaust port 5 is uncovered, whereupon the piston and head will drop, this operation being repeated in rapid succession as long as the 125 controlling valve is held in the position just described. The sand in the mold frame is thus jarred and evenly compacted therein. The surplus sand is then struck off level with the top of the flask and the board 69 130

put in place. The flask is then inverted or rolled over and placed upon head 7 with the bottom board 69 resting upon the head and the pattern plate resting upon the upper 5 end of the flask, as shown in Fig. 1. The arm 34 is then swung horizontally until rod 37 engages in slot 39 in the boss 40 formed on bracket 8.

This movement of the arm 34 carries pressure head 42 directly over the pressure head 7. The handle 14 is then turned to connect ports 19 and 20 through valve cavity 12, and thus admit air from the pipes 23 into the large cylinder 2 below squeezing piston 3 by 10 way of pipe 24 and recess 25, whereupon piston 3 will be forced upwardly, carrying with it the head 7 and the mold frame. As the head 7 moves upwardly, the pattern plate will abut against the under face of the 15 pressure head 42, compressing the sealing gasket 49 as shown in Fig. 6. The mold will be squeezed between the heads 7 and 42 and the bottom board 69 will be forced upwardly within the frame or flask section 66 20 firmly packing or ramming the sand about the patterns. When the squeezing operation is completed handle 60 of the valve 52 is turned to admit air through pipe 51 into cylinder 47 below the piston 48. This will 25 force the piston upwardly and draw inwardly and upwardly the piston 45 thereby creating a vacuum, or partial vacuum, between the pattern plate, the sealing gasket 49 and the piston 45. This vacuum will be 30 sufficiently high to cause the pattern plate to be tightly held against the pressure head 42. Handle 14 is then turned to connect 20 and 35 21 through cavity 12 to exhaust the air from cylinder 2 through pet cock 26, whereupon 40 the piston 3, head 7, and the flask frame 66 with the formed mold will move downwardly to their starting point. The pattern plate with the patterns attached thereto will be held to the under face of the head 42 be- 45 cause of the vacuum between the pattern plate and the piston 45, the sealing gasket 49 maintaining this vacuum so that the pattern plate will be held against the pressure head by atmospheric pressure. The patterns 50 held to the pattern plate are thus drawn from the mold automatically when the pressure heads 7 and 42 are separated at completion of the squeezing operation. This operation is shown in Fig. 7. The operator then 55 removes the flask. The head 42 and the arm 34 may be swung laterally to take the head 42 and the pattern plate out of alignment with the flask. When it is desired to release the pattern plate from the pressure 60 head it is only necessary to turn the handle 60 to exhaust air from the cylinder 47 and admit air to the cylinder 44. This position of the valve is shown in Fig. 6.

It will thus be seen that means have been 65 provided whereby molds may be jolted and

squeezed, and the patterns drawn therefrom and assembled with another mold frame with great rapidity.

What I claim is:

1. In a molding apparatus, the combination of relatively movable mold squeezing members, means for imparting a relative movement between said members, and pneumatic means on one of said members for holding a pattern against movement relatively to said member upon separation of the squeezing members. 70

2. In a molding apparatus, the combination of a vertically reciprocable mold support, a pattern-drawing pressure head, a laterally shiftable support for said head, and vacuum forming means carried by said head and adapted to hold the pattern plate when the mold support is moved away from said pressure head. 75

3. In a molding apparatus, the combination of a pattern plate, relatively reciprocable mold squeezing members, and means for forming a vacuum between the pattern plate and one of said members whereby when said members are separated the pattern plate will be held to one of said members by atmospheric pressure. 85

4. In a molding apparatus, the combination of a reciprocable flask support, a mold-squeezing and pattern-drawing head, a swinging support for said head whereby the head may be shifted into and out of alignment with the flask support, a flask mounted on the flask support, pattern-holding means 95 separably held to the flask, means for moving the flask support toward and from the head to squeeze a mold thereon, and operative means for creating a vacuum between the pattern-holding means and the pressure 100 head whereby when the flask support is separated from the head the pattern-holding means will be held to the under side of the pressure head by atmospheric pressure. 105

5. In a molding apparatus, the combination of relatively movable mold squeezing members, means for imparting a relative movement between said members, and means for forming a vacuum between one of said members and a pattern-holding plate, whereby said pattern-holding plate will be held against movement relatively to said member upon the separation of the members. 110

6. A mold squeezing and drawing apparatus comprising a pair of mold-squeezing members one of which is provided with a chamber in open communication with the working face thereof, means for moving one of said members toward and from the other, a piston reciprocable in said chamber, 120 and means for moving said piston in opposite directions at will, for the purpose set forth. 125

7. In a mold-squeezing and pattern-drawing apparatus, the combination of a pressure 130

and pattern-drawing head having a gasket in its working face adapted to seat against a pattern plate, said head having a chamber therein in open communication with the working face of the head within the gasket, a mold support, means for moving the mold support toward and from the working face of the head, a piston in said chamber, and means for moving said piston at will in opposite directions to hold a pattern plate to the head by suction and to release said plate.

8. In a molding apparatus, the combination of a mold-frame support, a pattern-plate engaging head, means for imparting a relative reciprocable movement between

said support and head to form a mold, a pair of aligned cylinders, pistons in said cylinders, means connecting the pistons to move in unison, a valve, and connections controlled by said valve for admitting and exhausting fluid pressure at adjacent faces of said pistons, said valve being provided with ports for exhausting each cylinder when pressure is admitted to the other cylinder, one of said cylinders being in communication at its outer end with the pattern-plate-engaging face of the head, for the purpose set forth.

In testimony whereof I hereunto affix my signature.

WILLIAM H. NICHOLLS.
